United States Patent Office.

JACOB EDSON, OF BOSTON, MASSACHUSETTS.

Letters Patent No. 101,842, dated April 12, 1870.

IMPROVEMENT IN MOLDS FOR CASTING PIPE.

The Schedule referred to in these Letters Patent and making part of the same.

To all whom it may concern:

I, JACOB EDSON, of Boston, in the county of Suffolk and State of Massachusetts, have invented certain new and useful Improvements in Molds for Casting Pipe, of which the following is a specification.

Nature and Object of the Invention.

The nature of my invention consists in so forming the core that it will of itself form a suitable end or buttress against which the metal will form, and, thus produced, being sufficient for the bearing or gasket, while the remainder of the flange may be sufficiently drawing to be molded in the ordinary manner, the object being to produce pipes with true bearing ends in a simple, cheap, and workmanlike manner.

Description of the Accompanying Drawing.

Figure 1 is a perspective view of a half flask, with a pattern and core points.

Figure 2 is a longitudinal section through the same. Figures 3, 4, and 5 are sections in detail.

General Description.

A B, figs. 1 and 5, represent the flask, which may be made, as shown in fig. 1, to suit the style of pipe.

K K' D C, fig. 1, represent the pattern, L L L being metallic cores for forming the bolt-holes in the flange.

C, figs. 2 and 5, represents the core-spindle.

D', in the same figures, represents the sand-core, and is made, as shown, with a shoulder, d, which forms the bearing-surface for the gasket. This shoulder d may be made so as to form a simple rabbet in the end of the pipe, as shown in fig. 2, or to form an annular sinkage, as shown in fig. 5.

The character and size of this rabbet or sinkage may be varied at will.

The core D' may be formed upon the spindle C by the ordinary process of "turning up" or it may be partially turned; and, in case the shoulder d is not readily made by this process, it may be molded, that is, formed in a suitable core-box.

That part of the flange H which extends beyond the core is made sufficiently drawing to admit of being molded in the ordinary manner.

In figs. 3 and 4 I have represented in section the ends of two pipes as they appear when bolted together, with the gasket M between them.

In fig. 3 the gasket is represented as being held by simple rabbets, while in fig. 4 it is held by a trapezoidal sinkage.

I claim as my invention—

The core D, with shoulders d, for casting flange-pipes or columns, substantially as described and for the purpose set forth.

JACOB EDSON.
